VALVE

John J. Slavin and Casper S. Stuckenholz, Cleveland, Ohio, assignors to The W. J. Schoenberg-er Company, Cleveland, Ohio, a corporation of Ohio

Application April 9, 1936, Serial No. 73,562

1 Claim. (Cl. 277—32)

Our invention relates to new and useful improvements in gas fixtures and has reference to gas cocks or valves of the rotary plug type which are provided with throttle screw adjustment means for accurately controlling the volume of gas flowing through the valve.

The general object of our invention is to provide a conveniently located inexpensive mounting for the throttle screw adjustment element.

10 A further object of the invention is to provide means for eliminating the objectionable whistling noise heretofore caused in valves of this general type when the throttle is adjusted to reduce the flow of gas to an approximate minimum.

15 A still further object of the invention is to provide efficient means for eliminating objectionable throttle valve vibrations.

Other objects and advantages will be apparent as the following description is considered with the accompanying drawing, in which:

20 Figure 1 is a plan view of a valve embodying the invention;

Figure 2 is a section through the casing on the line 2—2 of Figure 1, the plug valve being shown in full lines;

25 Figure 3 is a vertical section through the plug valve removed from the valve casing showing the throttle valve and closure members assembled;

Figure 4 is a side view of the throttle valve removed; and

30 Figure 5 is a fragmentary bottom plan view of the valve casing showing the washer in the position assumed when the plug valve is in full open position.

35 Referring more particularly to the drawing 1 denotes the cast metal valve body member or casing, centrally and longitudinally bored or chambered, as at 2, to provide a substantially cone-shaped seat 3 for a plug valve 4, rotatably mounted therein.

40 Extending at right angles to the bore 2 and in communication therewith at their inner ends, through axially aligned inlet and outlet passages 5 and 6, are two extensions or branches 7 and 8 respectively. The outer end of extension

45 7 is threaded externally, as at 9, for connection with a gas manifold, not shown, and the outer end of extension 8 is threaded internally, as at 10, for connection with the burner of a stove or the like, also not shown. A third extension or

50 branch 11, internally threaded as at 12, for connection with a pilot light not shown, communicates with the passage 6, through a small opening 13. Of course the connections could be reversed, that is, extension 8 connected to the

55 manifold and extension 7 to the burner.

The plug valve 4, which is externally tapered to snugly fit and turn within the seat 3 formed in bore 2 of the casing 1, has an integral extension or stem 14 provided with oppositely extending integral wings or handle portions 15. 5 Preferably the plug 4 has a longitudinally extending axial passage or bore 16, communicating respectively through transversely extending aligned oppositely disposed passages 17 and 18, with the inlet and outlet passages 5 and 6 in the 10 casing, when the valve is in open position.

Slidably but non-rotatably mounted upon the threaded lower end 19, of a reduced extension 20, depending from the plug valve 4, is a washer 21, cut away as at 22, to provide stop shoulders 23 15 and 24, adapted to cooperate with a lug 25 on the end wall 26 of casing 1, in limiting the movement of the plug valve. Thus, when the plug valve 4 has been rotated to the position shown in Figures 1 and 2, with the wings 15 extending parallel with the extensions or branches 7 and 8, the shoulder 23 engages one end wall of stop lug 25 and halts the valve in full open position. Upon clockwise rotation of the valve approximately forty-five degrees from this position, the shoulder 24 will engage the other end wall of stop 25, and the passages 17 and 18 in the plug valve will have been moved out of register with the passages 5 and 6 in the casing, thus closing the valve. In order to prevent independent rotation of the 20 washer with respect to the valve, the extension 20, has one or more flat faces, and the opening 30 in the washer is correspondingly shaped.

25 A coil spring 27, sleeved over the extension 20 engages with its upper end the lower face 35 of the washer 21, and seats at its lower end against a nut 28, threadedly mounted on the threaded end 19 of the extension 20, thus forcing the washer against the end wall 26 of the casing, and at the same time pulling the plug 40 valve resiliently to its seat. Preferably a lock nut 29 is employed to prevent the nut 28 from becoming accidentally unscrewed.

30 It will be noted that the round stem or extension 14 is much larger than the conventional valve 45 stem and in fact is a continuation of the plug valve 4 and is of substantially the same diameter as the latter. The central longitudinally disposed bore 16 in the plug valve 4 also continues on through the stem 14, and is screw threaded from 50 its upper end to a point slightly above the transverse inlet and outlet passages 17 and 18, for a purpose about to be described.

35 In order to provide for a better and more accurate control of gas volume flowing through the 55

fixture, than is had with the conventional plug valve, a throttle screw or valve 31 is threadedly mounted in the bore 16, of the plug valve 4 and its extension 14. The throttle valve 31 is formed 5 with a threaded enlargement 32, the threads of which mesh with the screw threads of bore 16, the lower portion of the throttle screw being unthreaded and terminating in a beveled end portion 33. When the throttle valve is screwed 10 home, this beveled end 33, seats against the correspondingly beveled bottom wall 34 of bore 16. The bottom wall 34, as will be noted from an inspection of Figures 2 and 3, is slightly below the transverse passages or openings 17 and 18, thus 15 forming a well 50 in which the lower end of the throttle valve is accommodated. While the fit of the throttle valve 31 in the bore 16 and well 50 is such as to permit of a very delicate adjustment being made, such fit is not so tight as to preclude 20 a slight flow or seepage of gas in through passage 17, around the unthreaded portion of the throttle and thence out through passage 18, when the plug valve is in open or partly closed position. This construction is desirable, where the fixture is pro- 25 vided with a pilot light connection on the outlet side of the casing, so that the pilot will be kept burning at all times when gas is being fed to the plug valve. Of course when the plug valve is turned to fully closed position with the passages 30 17 and 18 completely out of register with the respective passages 5 and 6, the flow of gas to both burner and pilot will be completely shut off. A screw cap 35 closes the outer end of the bore 16. Experience has proven that where the end of 35 the throttle is squared, objectional whistling was caused by the gas passing through passages 17 and 18 striking the sharp edges of the throttle screw. This whistling is obviated, and a much more uniform flow assured, by beveling the end 40 33 of the throttle.

Heretofore considerable trouble has been experienced with fittings of the general type disclosed herein, due to the fact that the throttle

valve would frequently be affected by vibrational stresses thus causing the gas rate to vary to an objectionable degree. This objectionable vibration has been eliminated in the present invention by a small coil spring 36, which seats at its inner 5 end against the end wall of a recess 37 formed in threaded enlargement 32, and at its other end against the threaded wall of longitudinal passage or bore 16 of plug valve 4.

The location of throttle adjustment screw or valve 31 in the plug 4 adds practically nothing to 10 the cost of the latter, as the only change necessary in the conventional plug is to extend the bore or passage 16. On the other hand the location of the throttle in the plug obviates the necessity of 15 forming the customary separate chamber or housing for the throttle on the casing 1, as well as changes in the plug. The extended outer hollow end or stem portion of the plug serves as a 20 housing for the throttle valve and at the same time the former can readily be cast with the wings or handle portions 15. Furthermore, by mounting the throttle axially in the hollow plug a much better control of the rather heavy gas flow present in fittings of this type, is possible. 25

Having thus described our invention, what we claim is:

A valve comprising a valve body having a valve seat, a plug valve rotatably confined in said seat, said valve body and plug having communicating 30 inlet and outlet passages, said plug having a bore in axial alignment with the valve seat, a throttle valve screwed in the upper end of the bore and having a smooth lower end controlling the flow of 35 gas through the plug and of a diameter less than the bore to allow a certain amount of gas to pass through the plug in all positions of the throttle valve, and a resilient engaging means between the plug and the throttle valve to hold the plug against longitudinal movement and vibration. 40
